UNITED STATES PATENT OFFICE.

JAMES ENGLAND, OF NEW YORK, N. Y.

SUSPENDER-BUCKLE.

SPECIFICATION forming part of Letters Patent No. 397,634, dated February 12, 1889.

Application filed June 25, 1888. Serial No. 278,161. (No model.)

To all whom it may concern:

Be it known that I, JAMES ENGLAND, of the city, county, and State of New York, have invented a new and Improved Suspender-
5 Buckle, of which the following is a full, clear, and exact description.

The object of my invention is a buckle which will retain its hold upon the web when the toothed bar is turned downward or outward; and it consists in the parts which will be hereinafter described, and pointed out in the claims.

Reference is to be had to the accompanying drawings, forming a part of this specification, 15 in which similar letters of reference indicate corresponding parts in all the figures.

Figure 1 is a rear view of the buckle engaged to a suspender, the lower end of the web being shown in dotted lines. Fig. 2 is a section on the line *x x* of Fig. 1. Fig. 3 is a section on the line *y y* of Fig. 1, and Fig. 4 is a rear perspective view with the hinge-plate detached.

The base-plate A of the buckle is provided 25 with outwardly-extending apertured ears A' A', and with a hook, B, at its lower end to receive the loop G, attached by the strap H to the suspender-ends J J. A bar, F, provided with a double row of reversely-inclined teeth, 30 F² F³, is pivoted by its ends F' in the ears A' of the plate A. A plate, C, having inwardly-extending end flanges, D D, and bottom flange, E, provided, respectively, with the lugs e and e', is attached to the bar F, so that said bar is 35 above the flanges D and its ends F' extend beyond the plate, by which ends the bar F and plate C are hinged to the plate A.

The bar F, as shown, is provided with a longitudinal row of teeth, F², a number of which 40 (every third one, F³) are bent upward to project at an angle of forty-five degrees to the others, thereby forming a double row of teeth; but the two rows of teeth might be otherwise produced.

45 The suspender-web K is passed between the

plates A and C, and the buckle is held in place by passing down the plate C. When the toothed bar and plate C are in the position shown in Figs. 1 and 2, the web is engaged by the row of teeth F², and the loop G 50 is prevented from accidental displacement from the hook B by means of the lug e'. When it is desired to disengage the loop G from the hook B, the toothed bar and plate C are turned outward to the position shown in dotted lines, 55 Fig. 2. When in that position, the loop may be disengaged from the hook. It will be observed that while in said position the upper row of teeth, F³, are in contact with the web, while the lower row, F², are out of contact 60 with said web. By moving the toothed bar and its plate farther upward from the position shown in dotted lines both rows of teeth F² F³ will be out of contact with the web, so as to permit the buckle to be removed from 65 the web at pleasure.

Having thus described my invention, what I claim as new, and desire to secure by Letters Patent, is—

1. In a buckle, a plate provided with a hook, 70 B, in combination with a bar pivoted to said plate, said bar being provided with a lug, e', and also provided with teeth inclined at a different angle, substantially as shown and described.

2. A buckle consisting of a base-plate having outwardly-extending apertured ears, a bar provided with side journals, said journals being mounted in the ears aforesaid, said bar being also provided with a longitudinal row 80 of teeth, one or more of the teeth in said row being inclined at a different angle from the others, each tooth having the same axis and each movable in the same arc, substantially as described.

JAMES ENGLAND.
